(57) **CLAIM**

The ornamental design for a skateboard truck, as shown and described.

DESCRIPTION

FIG. 1 is a perspective view of the skateboard truck;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a bottom plan view thereof; and,

FIG. 7 is another perspective view thereof.

The portions of the skateboard truck shown in broken lines in FIG. 6 form no part of the claimed design.

The broken lines in FIGS. 1-4, 6 & 7 represent portions of the article that form no part of the claim.
